UNITED STATES PATENT OFFICE

117,104

DESIGN FOR A SHOE

Roy Maling, West Roxbury, Mass.

Application June 10, 1939, Serial No. 85,447

Term of patent 7 years

To whom it may concern:

Be it known that I, Roy Maling, a citizen of the United States, residing at West Roxbury, in the county of Suffolk and State of Massachusetts, have invented a new, original, and ornamental Design for a Shoe, of which the following is a specification, reference being had to the accompanying drawing, forming part thereof.

In the drawing:

Figure 1 is a side elevation of a shoe showing my new design. The design is substantially the same on both sides of the shoe; and

Figure 2 is a top plan of the shoe of Figure 1.

The essential feature of the invention resides in a wedge-shaped lift which lends curvature to the shank above a sole or sole platform which has a heel attached at its under side. As the design is applicable to shoes of various shapes and styles, the representation of shoe is conventional, for showing an application of the design.

I claim:

The ornamental design for a shoe as shown and described.

ROY MALING.
